UNITED STATES PATENT OFFICE.

HENRY M. BEIDLER, OF TEXARKANA, ARKANSAS.

GALVANIC BELT.

SPECIFICATION forming part of Letters Patent No. 335,417, dated February 2, 1886.

Application filed December 16, 1884. Renewed July 21, 1885. Serial No. 172,339. (No model.)

To all whom it may concern:

Be it known that I, HENRY M. BEIDLER, a citizen of the United States, residing at Texarkana, in the county of Miller and State of Arkansas, have invented certain new and useful Improvements in Galvanic Belts; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to an improved device for applying electric currents to the animal body for therapeutic purposes, its object being to facilitate the application of currents in any desired direction through the body.

The improvement may be fully understood from the following particular description, in connection with the accompanying drawings, in which—

Figure 1 is an inside view of an extended body-belt provided with electric appliances according to my invention. Fig. 2 is an edge-wise view of the belt with its ends clasped together. Fig. 3 is a rear perspective view of the battery detached. Fig. 4 is an edgewise view of the same. Fig. 5 is a diametric section of the battery. Fig. 6 is a perspective view of the adjustable electrode.

The battery A, I construct in the form of a pad, and its voltaic elements are inclosed by a flat case, the two parts *a* and *a'* of which fit together substantially like the two parts of a blacking-box. The part *a* is formed of an impervious non-conducting material—such as hard rubber or celluloid—and the part *a'* is made of sheet metal—preferably copper—and is corrugated, for the purpose of gaining surface within given superficial limits. When these two parts are put together, as shown in Fig. 5, they inclose between them the voltaic elements of which *z* is a zinc plate next to the non-conducting part *a* of the casing, and *c* is a copper plate next to the copper or conducting side *a'* of said casing. Between these two plates *z* and *c* is an absorbent disk, *f*, preferably of felt, though any other non-conducting or semi-conducting absorbent material would answer, and it should be in contact with both of the plates between which it lies. The non-

conducting part *a* of the casing has attached to its inner surface one end of a metallic spring, *s*, the other end of which bears against the zinc plate *z*, and the conducting part *a'* has attached to its inner surface, preferably, a metallic spring, *s'*, which presses against the copper plate *c*, for the purpose of making a good electrical connection, though the metallic part of the casing might come in direct contact with the copper plate for the same purpose.

On the back of the non-conducting part *a* is riveted a bracket or slide, *d*, of metal, and the rivets which secure it at one end serve also to hold the spring *s*, so that metallic connection is established between the bracket and spring. The belt *B*, which may be made of leather or any other suitable material, passes through the bracket or slide *d* loosely, so that the battery may be slid along to any desired position upon said belt.

The letter *E* indicates an adjustable electrode, which also slides upon the belt. This electrode comprises two open-work metallic plates, *e* and *e'*, which are hinged together, and are arranged upon the inner surface of the belt, so that they will come in contact with the body to which the belt is applied. They are held upon the belt by means of metallic brackets or slides, similar to that of the battery, and the bracket of the battery is connected by a covered wire, *w*, or other flexible conductor with the bracket of one portion of the adjustable electrode.

In order to charge the battery, I saturate the absorbent disk *f*, between the zinc and copper plates, with an acidulated liquid—say acetic acid or vinegar—and it is then ready for use.

It will be understood that the conducting or copper part *a'* of the battery-casing serves as an electrode connected with the voltaic elements, and comes in direct contact with a body to which the belt is applied, and when the metallic part and the other adjustable electrode are in contact with the body at different points the current of electricity from the battery will flow from its copper part or wall through the body to the other electrode, and thence over the wire *w* to the bracket and opposite pole of the battery.

The battery and the electrode *E*, both being capable of sliding on the belt, may be adjusted

to any relative positions, in order to cause electric currents to pass through the body in any desired direction.

The belt may be of any desired size, and 5 may be applied to the head or limbs, as well as the trunk of the body.

A knowledge of the therapeutic effects of electric currents is now so widely spread that it is unnecessary to here enumerate the various 10 diseases for the cure or alleviation of which my invention may be used. Suffice it to say that for all ailments in which treatment by constant electric currents is indicated it may be conveniently applied with salutary results.

15 I wish it to be understood that I do not confine myself to any particular pair of voltaic elements or exciting fluid in the interior of the battery, it being only necessary that one of the battery-poles shall be connected with 20 the metallic part or body-electrode of the casing and the other pole shall be connected with the adjustable electrode. I prefer to make this adjustable electrode of two jointed open-work plates, as shown; but a single plain-surfaced 25 metallic plate might be used.

Having now described my invention, and explained the manner of using the same, I claim—

1. The combination, with the battery inclosed in a casing which is adjustable upon a belt and one of the walls of which forms a body-electrode, of the adjustable opposite electrode mounted upon the same belt and electrically connected with the pole of the battery opposite that which is connected with its said body-electrode, substantially as described. 30

2. The combination, with a battery inclosed in a flat casing adjustable upon a belt, as described, and having one of its side walls formed of non-conducting material and the other of corrugated sheet metal forming a body-electrode, of the flexible electrode mounted upon the same belt and connected with the battery, as set forth. 40

In testimony whereof I affix my signature in presence of two witnesses.

HENRY M. BEIDLER.
